RAILWAY SIGNALING

Application filed August 4, 1925. Serial No. 48,030.

This invention relates to railways, more especially to railway track circuit signaling and particularly to a support for a cable bonded to the rail.

5 In practice, as is well understood by those skilled in the railway signaling art, it is necessary to electrically bond an electrical conductor, as a cable, to the web of a rail.

This cable, especially, if of the form known 10 as parkway cable, as is now commonly used, is buried in the ground and emerges therefrom adjacent the point where it is to be connected to the rail. It has been found necessary to rigidly attach this cable to the 15 rail by means other than the bonding connection so that in case the rail vibrates unduly, the effect will not be concentrated at the point of bonding, as the cable would soon break. Furthermore, if the rail "runs" 20 duly a severe strain, perhaps breaking the bonding will occur unless the cable is attached rigidly to the rail at some point on the cable where the full cross section of the cable may be taken advantage of.

25 A principle object of applicants' invention is to provide a means for supporting a cable on a rail so that the difficulties hereinbefore mentioned will be avoided.

Other objects and advantages will appear 30 as the description of the particular physical embodiment selected to illustrate the invention progresses and the novel features of the invention will be pointed out in the appended claims.

35 In describing the invention in detail and the particular physical embodiment selected to illustrate the invention reference will be had to the accompanying drawing wherein has been illustrated a preferred physical embodiment of the invention and wherein like characters of reference designate corresponding parts throughout the several views in which:

Figure 1 is a side elevational view of a 45 fragment of railway rail with our invention applied thereto; Fig. 2, is a cross sectional view on the plane indicated by the line II—II of Fig. 1; Fig. 3, is a cross sectional view on the plane indicated by the line III—III of Fig. 1; Fig. 4, is a view illustrating a clip

used with the invention, before being formed; Fig. 5, illustrates a perspective view of a clip, used in the invention, after being formed.

In the drawing, 1 designates a railway rail. 2 designates a bonding pin used to 55 mechanically and electrically attach the bared end 3 of cable or wire 4 to the web of the rail 1.

In order to rigidly support cable 4 and hold the same firmly to the rail at a point 60 where the full cross section of the wire or cable may be availed of, applicants provide two similarly formed but oppositely disposed clamping plates 5 and 6. These plates have an orifice in each end and are disposed on opposite sides of the cable 4 with plate 6 bearing against the edge of the flange of the rail. 65

Applicants pass the hook 7 of a hook bolt 8 through the orifice of each plate and rest 70 the end 9 thereof on the upper face of the flange of the rail.

The threaded end of the hook bolt is passed 75 through the lug 10 of the rail clip, designated as a whole by 11 and the rail clip is fitted to the flange of the rail, as shown in Fig. 2, and then the nut 12 is put in place and tightened.

From the foregoing description it will be readily understood that the cable 4 is rigidly 80 and firmly attached to the rail 1 at a point where the full cross section of the wire may be taken advantage of and that if the rail vibrates, this vibration will not be concentrated at or about pin 2 because the cable being held rigidly at the cable support, the portion 85 3 and the rail will move together, not independently. Furthermore if the rail "runs" the strain will be applied to the support and not to the pin 2.

Applicants having described their invention and a particular physical embodiment selected to illustrate the invention, nevertheless, desire to have it understood that the form selected is merely illustrative and does not exhaust the possible tangible embodiments 95 of the means underlying the invention.

What we claim and desire to secure by Letters Patent of the United States, is:

1. As a cable support adapted to hold a cable firmly to a rail, the combination of a 100

clip adapted to engage a flange of a rail of a hook bolt adapted to be held in place on one edge of the opposite flange of a rail by the clip and oppositely disposed orificed clamping plates holding a cable therebetween and against the other edge of the rail flange by having the hook of the bolt pass through both the orifices formed in one end of the plates and the orifices formed in the other end of the plates said hook bolt adapted to have the end of the hook rest on the upper face of the flange of the rail.

2. As a cable support for holding a cable firmly to a rail; a clip formed for engagement with a rail flange and adapted to bear both on the edge and the upper and the lower face and formed with a depending lug formed with an orifice; a hook bolt passing through the orifice in the said lug and provided with a nut bearing thereagainst; a clamping plate adapted to bear against the opposite edge of the flange of the rail and formed with an orifice in each end; another clamping plate opposed to the first clamping plate and formed with an orifice in each end matching the orifice of the first mentioned plate, and the hook of the hook bolt adapted to pass through the orifice and adapted to have its free end rest on the upper face of the flange of the rail whereby when the nut is tightened with a cable between the plates all parts are adapted to be held firmly and immovably to the rail.
